UNITED STATES PATENT OFFICE.

JULIUS A. DIDSCHEUNEIT, OF CAMDEN, SOUTH CAROLINA.

HEAD-REST FOR BARBERS' CHAIRS.

1,187,720.

Specification of Letters Patent. Patented June 20, 1916.

Application filed August 4, 1915. Serial No. 43,652.

To all whom it may concern:

Be it known that I, JULIUS A. DIDSCHEUNEIT, a citizen of the United States, residing at Camden, in the county of Kershaw, State 5 of South Carolina, have invented certain new and useful Improvements in Head-Rests for Barbers' Chairs; and I do hereby declare the following to be a full, clear, and exact description of the invention, such as 10 will enable other skilled in the art to which it appertains to make and use the same.

This invention relates to improvements in head rests, and particularly to devices for use by barbers in holding a child's head 15 while cutting the hair.

One object of the present invention is to provide a simple and novel device of this character which can be readily applied to the arms of a chair.

Another object is to provide a device of this character which will hold the child's head up in the proper position, and which will hold the body erect.

Other objects and advantages will be apparent from the following description when taken in connection with the accompanying drawing.

In the drawing: Figure 1 is a front elevation of the device attached to a barber's chair. Fig. 2 is a side elevation of the same. Fig. 3 is a top plan view, and Fig. 4 is a transverse sectional view on the line 4-4 of Fig. 1.

Referring particularly to the accompanying drawing, 10 represents the arm of a barber's chair. A horizontal arm 11 extends transversely of the chair and is provided with a rubber cover jaw 11' which engages the upper side of the chair arm. A second jaw 12 extends beneath the chair arm and carries a clamp screw 13, provided with a rotatable head 14 for engagement with the under side of the chair arm. Thus, the top and bottom faces of the chair arm are protected from the jaws of the clamp which se-

curely hold the arm 11 in proper position. An angle member 15 has one of its arms slidably disposed through the inner end of the arm, and adjustable by means of the screw 16. Carried by the horizontal portion of the 50 member 15 is a vertically adjustable post 17, the upper end of which is provided with a chin rest pad 18. Carried by the horizontal arm of the angle member is a pair of pads 19 which are arranged to bear against 55 the back of the child's shoulders to hold the child forward from the back of the chair, and in an erect position.

All of the parts are adjustable so that the barber can place the child in any position 60 desired, and which will facilitate the easy cutting of the hair.

One principal feature, to which attention is particularly called is the chin rest, by means of which the child's head can be held 65 up. The general tendency of a child is to lower its head forwardly, and while in this position, it is very difficult to properly cut the hair in front.

The device is simple in construction, and 70 easy of operation, and can be quickly and easily attached to or detached from the ordinary barber's chair without any modifications to the chair or its parts.

What is claimed is:

A device for holding a child's head while in a barber's chair, comprising an arm detachably secured to the arm of the chair, a vertically and horizontally adjustable chin rest carried by the arm, and shoulder pads 80 also carried by the arm for engagement with the backs of the child's shoulders to hold the child in an upright position.

In testimony whereof, I affix my signature, in the presence of two witnesses.

JULIUS A. DIDSCHEUNEIT.
